HYDRAULICALLY OPERATED CASKET
TABLE FOR HEARSE

Edward Richter, Freeport, Ill.

Application February 4, 1935, Serial No. 4,729

45 Claims. (Cl. 214—65)

This invention relates to hearses of the side delivery type.

The casket table in a side delivery hearse is guided for movement from a longitudinal position in the hearse to a transverse position extending from either side of the hearse. Hearses have been constructed to provide either for manual operation entirely or interchangeable manual or power operation. The interchangeable type heretofore involved the meshing and unmeshing of gears and was not fool-proof. It is, therefore, one of the principal objects of my invention to provide a hydraulic table operating mechanism which is more easily convertible from power operation to manual operation, or vice versa, there being no gears to mesh and unmesh, and which is virtually fool-proof under all operating conditions.

The most improved table operating mechanism thus far devised involved the use of a reversible electric motor driving a long screw normally engaging a worm gear on the casket table. This mechanism, while reasonably satisfactory, was subject to the objection mentioned before—namely, that it required the throwing of gears into and out of mesh, the worm gear being disengagable from the screw by manipulation of a lever. In accordance with my invention, a hydraulic piston and cylinder are provided for operating the table, having in connection therewith an oil pump driven by a single uni-directional electric motor, and a valve movable to either one of two power operating positions to deliver the oil selectively to either end of the cylinder and drain oil from the other end, the valve being also arranged to be moved to an intermediate neutral position in which movement of the table by hand is permitted, the oil under such conditions being conducted simply from one end of the cylinder to the other. Aside from the advantage of a simpler fool-proof gearless construction, the hydraulic mechanism offers smoother operation with hardly a perceptible sound.

Another important feature of my improved hydraulic mechanism is the provision of an overload release or safety valve in the hydraulic circuit which, in the event of the table encountering an obstruction, is arranged to open and by-pass oil so that no damage can occur to the table or any part of the mechanism. With the electrically operated mechanisms, the screw necessarily operated in the disengageable worm gear with such a speed reduction that considerable force could be applied by the table to anything obstructing its movement before the motor would be stalled, and

serious damage was apt to result either from careless operation or in the event some fault developed in the mechanism or in the table guides.

Still another important feature is the provision of automatic switching means so related to the valve that the operation of the valve for selecting the direction of movement throws the motor into operation, and other switch means operable automatically at the limits of movement of the table to open contacts to stop the motor but at the same time close other contacts, which upon operation of the valve for the reverse movement of the table, will complete another circuit for the motor. Still another switch means is provided in series with these other switches operable automatically in the turning of a table guide switch from its neutral table locking position, whereby to positively prevent closing of the motor circuit if the valve is operated before the table guide switch has been turned to an open position to allow movement of the table. The table guide switch being operable by movement forward of either seat to designate the route of table movement to the right or left side of the hearse, according to which seat is moved, there is not only definite assurance that the table guide switch is opened before the motor circuit can be completed, but also assurance that the table will move in the proper direction and has ample room for its movement.

The invention will be better understood from the following detailed description in which reference is made to the accompanying drawings, wherein—

Figure 1 is a horizontal section through the body of a hearse showing the casket table in plan view with the right seat moved forward to permit movement of the table to and from the position shown in dotted lines;

Fig. 2 is a somewhat diagrammatic view showing a portion of the mound and its skeleton frame partly in plan and partly in horizontal section, and showing the table guides and hydraulic operating mechanism in plan view;

Figs. 3a—3b together show a longitudinal section on the line 3—3 of Figure 1 with an intermediate portion of the table, mound, and cylinder broken away between the dot and dash lines to permit showing the parts on a larger scale;

Fig. 4 is a longitudinal section corresponding to Fig. 3a but showing the piston moved to its forward limit;

Fig. 5 is a cross-section on the line 5—5 of Fig. 3b;

Fig. 6 is a front view of the valve showing one

of the contacts in elevation and the other in section;

Fig. 7 is a rear view of the valve;

Fig. 8 is a central, longitudinal section through 5 the valve;

Fig. 9 is a cross-section on the line 9—9 of Fig. 8 showing the stator port arrangement;

Fig. 10 is a plan view of the rotor illustrating its port arrangement;

10 Fig. 11 is a cross-section in a plane parallel to Fig. 9 but through the rotor and showing the rotor in one of its three operative positions;

Fig. 12 is a view showing the electric motor in plan view and the oil pump and reservoir in horizontal section;

15 Figs. 13 and 14 are cross-sections on the correspondingly numbered lines of Fig. 12;

Figs. 15 and 16 are horizontal, sectional details on the correspondingly numbered lines of Fig. 3a;

20 Fig. 17 is a section similar to Fig. 16 but showing the parts in a different relationship;

Fig. 18 is a vertical section through the switch arranged to be operated by the piston at the limits of its movement, and

25 Figs. 19 and 20 are combination electric and oil circuit diagrams, Fig. 19 showing the valve in its third or neutral position permitting hand operation of the table when either of the seats is moved forward to accordingly open the table guide

30 switch in the proper direction, and Fig. 20 showing the valve in one of its other two positions for power operation of the table forwardly, the table guide switch being shown in a position for movement of the table out to the right.

35 The same reference numerals are applied to corresponding parts throughout the views.

Referring first in a general way to Figures 1 and 2, 21 designates the body of a hearse having the usual doors 22 for use of the driver and a 40 passenger occupying seats 23 and 24, and having other side doors 25 arranged to be opened only when a casket is to be loaded or unloaded from the side of the hearse. A rear door 26 is also provided through which the casket may be removed 45 in the ordinary way when occasion arises. The casket (not shown) is supported on the table 27 movable relative to a raised platform or "mound" 28 which extends the full length of the body from the rear door 26 up to the seats 23—24. The 50 table is guided in its movement to and from the dotted line extended position by three guide members 29, 30, and 31. The front guide member 29 is in the form of a headed pin or stud projecting downwardly from the bottom of the table and arranged to be locked behind and beneath the 55 rim of a table guide switch 32, as disclosed in Figs. 3a and 15. The arcuate groove 33 in the switch 32 is arranged to direct the guide member 29 into the right or left one of two short guides 34 when the switch is turned to the proper position. Thus, the guide member 29 is movable 60 toward the right when the switch 32 is turned to the position shown in Fig. 2. The second or middle guide member 30 may be a pin or roller also projecting downwardly from the bottom of the table 27 for movement in either of two guides 35 branching from the main longitudinal guide 36 wherein the third and main guide member 31 operates. The latter is usually referred to as 65 the shuttle because it operates back and forth in the one guide 36. It serves to support the table 27 against tilting when it is in the dotted line position of Figure 1 and the casket is moved out onto the outer end thereof. Casters 37 distributed on the mound 28, as indicated in full and

dotted lines in Figure 1, support the table for easy rolling action.

Referring now to Figures 1—5, handles 38 on the front end of the table are arranged to be used in pulling the table out and moving it back. The table is, however, generally operated under power, there being a link 39 connecting the shuttle 31 with a cross-head 40 movable lengthwise of a cylinder 41 suitably supported at its front and rear ends on the frame of the mound 28, as at 42 and 43, respectively. The cylinder 41 is the working cylinder of the hydraulic table operating mechanism and contains a piston 44 having a rod 45 extending therefrom through the front end of the cylinder and connected, as at 46, to the front end of a tube 47, the rear end of which is attached to the crosshead 40, as at 48. A guide rod 49, suitably supported on the frame of the hearse at its forward end, as at 50, is received at its rear end in the tube 47 and forms a 20 guide for the front end of the piston rod 45 in the extension thereof from the cylinder 41, as shown in Fig. 4, thus preventing sagging of the rod and consequent binding in the end of the cylinder. The floor of the hearse in front of 25 the mound is formed with a raised portion 51 extending fore and aft between the seats 23—24 to provide clearance for the end of the piston rod 45 and crosshead 46 when moved forward.

As appears in Figures 1, 2, and 3a, the seats 30 23 and 24 are attached to guide rods 53 and 54, respectively, slidable in tubular guides 53a and 54a, projecting forwardly from the front wall of the mound 28. The rods project rearwardly under the mound for connection by means of 35 links 53b and 54b with arms 53c and 54c, respectively. The latter, as disclosed in the copending application of Earl L. Schofield and myself, Serial No. 1,750, filed January 14, 1935, are arranged to operate the switch member 32 40 through the medium of a T member 55 fastened to the downwardly projecting stem 56 of said switch member. The mode of operation is fully explained in the other application and should be clear from Figs. 16 and 17. When the right 45 seat 24 is moved forward, the rod 54 swings the arm 54c in a counterclockwise direction from the position of Fig. 16 to that of Fig. 17 and accordingly turns the T member 55 and with it the switch member 32 from the closed position 50 of Figs. 3a, 15, or 19, to the open position of Fig. 2 or 20, thereby designating a route of table movement to the right side of the hearse body from the full line position of the table in Figure 1 to the dotted line position. The route of table movement is determined according to which seat 55 is moved. Obviously, when either seat has been moved forward, it offers the required clearance for the table to move in and out behind it. When one seat is slid forward, the other seat is not free to move, it being held against movement by the T member 55, see Fig. 17. The stop 57 projecting downwardly from the housing 58 in which the switch 32 operates, limits the movement of the T member 55, as clearly appears in Fig. 17, 65 and accordingly limits the movement of the seats. The seats are releasably locked in the normal and forward positions by latches 59 cooperating with notches in the rods 53 and 54, as disclosed in the copending application aforesaid. The 70 knobs 60 projecting from the sides of the mound at the front end may be pulled out by hand to release either seat for movement forward or back, and there is provided alongside these knobs the levers 61 and 62 on opposite sides of the 75

mound for throwing the hydraulic table operating mechanism into operation, said levers being swingable forwardly, as hereinafter described, to produce power operation of the table forwardly and out of the hearse through either side, and being swingable rearwardly for the return movement. An intermediate position of the levers, as hereinafter described, is a neutral position so far as power operation is concerned and permits manual operation of the table in either direction.

Referring now mainly to Figs. 2, 19, and 20, the levers 61 and 62 are provided on opposite ends of a cross-rod 63 in the mound 28, having a lever 64 thereon connected by means of a link 65 with the control lever 66 of a valve 67. The latter has connections *a* and *b* with the opposite ends of the cylinder 41 to supply oil under pressure selectively to either end and simultaneously exhaust oil from the other end to accordingly move the piston 44 back and forth. The oil under pressure is supplied to the valve 67 through a pipe connection *c* from a pump 68 in the reservoir 69 and the oil exhausted from the cylinder is returned from the valve 67 to the reservoir 69 through another pipe connection *d*. The pump in the reservoir 68 is, of course, operated only long enough to move the piston to one end or the other of the cylinder and accordingly move the table all the way in or out. A single unidirectional electric motor 70 drives the pump and is connected with a storage battery 71 through a relay 72. There are three switches connected with the relay 72, all of which must be closed before the relay will be energized and throw the motor into operation. The first of these is switch 73 which is normally open but is closed when the table guide switch 32 is turned to open position by either of the arms 53c—54c. The second is a switch 74 which is normally closed two ways but arranged to have one phase opened when the arm 75 thereof is moved in one direction by a striker 76 on the crosshead 46 when the operating piston reaches the limit of its rearward movement, and arranged to have the other phase opened when the arm 75 is moved in the opposite direction by another striker 77 on the crosshead 46 when the operating piston reaches the limit of its forward movement (see Fig. 4). The third switch is designated 78 and is closed in one phase when the control lever 66 of the valve 67 is swung forward, as in Fig. 20, for forward movement of the table, or is closed in its other phase when the lever 66 is swung to the rear for rearward movement of the table. The operation can be followed by observing Figs. 19 and 20.

Power operation

In Fig. 20, the hand lever 61 is shown as swung forward to produce forward and outward movement of the table 27. At the moment that that is done, however, the arm 75 of the switch 74 is in the position of Fig. 19 with only the right hand phase of the switch in closed circuit. The circuit is, therefore, as follows—Starting with the fact that the table guide switch 32 is grounded at switch 73, current flows through the conductor 79 through the right hand phase of switch 74 to the conductor 80; then through the left hand phase of switch 78 to the control lever 66 and the conductor 81 extending therefrom to the coil of the relay 72, and from the coil through the battery 71 to the ground again. Its coil being energized, the relay 72 closes the circuit for the motor 70 in an obvious manner. The pump 68

is, therefore, operated to pump oil from the reservoir 69 through the pipe *c* to the valve 67. The oil is delivered under pressure from the valve through the pipe *b* to the rear end of the cylinder 41, thereby moving the piston 44 forward and accordingly moving the table 27 forward and out through the right hand side of the hearse, the switch 32 being thrown in that direction. Oil is exhausted from in front of the piston 44 through the pipe *a* to the valve 67 and flows from the valve through pipe *d* and back to the reservoir 69. When the piston 44 nearly reaches the front end of the cylinder, the striker 77 encounters the arm 75 and opens the right hand phase of the switch 74, accordingly de-energizing the relay 72 and stopping the motor 70. Under these conditions, the left hand phase of the switch 74 is left closed and accordingly when the hand lever 61 is swung to the rear to close the right hand phase of switch 78, the circuit is closed again through the coil of the relay 72 from the left hand phase of switch 74 through conductor 82 to the switch 78 and through conductor 81 to the relay 72, thus throwing the motor 70 into operation again. With the lever 66 in this position, as will be explained in connection with the description of the valve 67, the oil delivered from the pump 68 under pressure to the valve 67 through the pipe *c* is delivered through the pipe *a* from the valve to the front end of the cylinder 41 to produce rearward movement of the piston 44 and accordingly return the table 27 to its normal position. The oil exhausted from the cylinder 41 behind the piston 44 is conducted through pipe *b* to the valve 67 and from there through pipe *d* back to the reservoir 69. A pressure relief valve 83 in the pipe connection *c* is arranged to discharge back into the reservoir 69 and is set to open at a certain pressure well above the pressure required to move the table 27 when normally loaded. Thus, in case the table encounters any obstruction on the mound 28, or elsewhere in the hearse, or encounters any obstruction outside the hearse, seriously resisting movement of the table, the valve 83 opens and by-passes the oil from the pump 68 directly back to the reservoir 69 and will continue to do so until the trouble is remedied. Under those conditions, the proper thing to do is to reverse the valve 67 so as to back the table away from the obstruction, before continuing the forward movement with the obstruction removed or the hearse moved to a position allowing free movement of the table. Otherwise, the control lever 66 of the valve 67 may be moved to the neutral position shown in Fig. 19, in which hand operation of the table is permitted, in which case the table can be backed away by hand from the obstruction and power operation resumed after the difficulty interfering with power operation has been remedied.

Manual operation

Referring to Fig. 19, it is evident that with the control lever 66 of the valve 67 in mid position, the motor circuit could not possibly be completed even when the switch 73 is closed, as in Fig. 20, by the moving forward of one of the seats preparatory to moving the table. The reason is that the switch 78 is kept open when the lever 66 does not engage the right or left hand contact. In this position of the valve, as will better appear later, the pipe connection *c* from the pump 68 is entirely cut off from communication with the cylinder 41, and the pipes *a* and *b* are thrown into communication with one another

and with the pipe *d*. Thus, if the table is pulled forward and out by hand, using the handles 38, the oil from in front of the piston 44 will flow out through pipe *a* and back into the cylinder behind the piston through pipe *b*. However, because of the displacement due to the piston rod 45, less oil will be exhausted from in front of the piston than it takes to fill the cylinder behind the piston. The difference is made up by oil drawn in from the reservoir 69 through the pipe *d*. In other words, the cylinder 41 is kept completely filled on both sides of the piston. In the return movement of the table there is, of course, more oil being discharged from the cylinder through pipe *b* than is required to fill the cylinder on the other side of the piston through pipe *a* and the surplus oil is exhausted through pipe *d* to the reservoir 69.

I shall also describe presently how, by virtue of special construction of the valve 67, the table may be moved by hand during power operation when it is desired, for any reason, to speed up the operation. One can easily move the table by hand faster than it would be moved by power, and the hydraulic mechanism automatically resumes the operation of the table from whatever point it is moved by hand, and brings the table all the way out or all the way in, depending on the direction of operation.

The difference in volumetric capacity of the cylinder 41 on opposite sides of the piston 44, due to the piston rod 45, results in a slight increase in the speed of operation of the table on the return movements, the pump 68 being operated at a constant speed and having substantially constant delivery. This increased speed coming as it does in the loading of the casket into the hearse, or when the hearse is starting its return trip, is considered an advantage rather than an objection.

40 Valve 67

The valve 67 is fully illustrated in Figs. 6-11. It comprises a cast body or stator 84 onto which a bonnet 85 is bolted and enclosing a rotary disk or rotor 86, the flat bottom face of which makes sealing contact with the flat top surface of the stator. A separate stem 87, to which the lever 66 previously mentioned is attached, is slidably coupled to the rotor within a sleeve 88, as at 89, and a coiled compression spring 90 surrounding the sleeve bears on the rotor to keep it in proper sealing engagement with the stator. This spring at the same time serves by engagement at its other end with a washer to urge an inwardly facing cup leather 91 into a stuffing box 92 against one side of an annular flange 93 provided on the stem 87 to provide an oil tight seal and prevent leakage along the stem. The flange 93 serves as a packing gland and further aids in effecting a good seal. Behind this flange is a metal washer 94 and packing material 95 which, taken with the other features mentioned, eliminate the question of leakage entirely. A spring pressed ball detent 96 in the bonnet 85 next to the projecting end of the stem 87 releasably locks the lever 66 and rotor 86 in adjusted position, three circumferentially spaced recesses being provided therefor in the hub of the lever 66 to accommodate the ball detent in the three different positions of the valve. The ball detent is also of importance because it further insures maintaining good contact between the insulated terminal 97 on the lever 66 and either of the insulated terminals 78a and 78b forming the switch 78 previously mentioned. Spring pressed balls are provided in the ends of

the terminals 78a—78b for engagement with the terminal 97, thus further insuring maintenance of a good electrical connection when the lever 66 is swung into engagement with either of these terminals.

The port arrangement in the stator 84 should be clear from Figs. 7 and 9. Ports *a'* and *b'* communicate directly with pipes *a* and *b*, respectively, whereas, ports *c'* and *d'* communicate with pipes *c* and *d*, respectively, through cored passages in the bottom of the stator. The rotor 86 has two large ports *e* and *f* arranged to register with the ports *a'* and *b'* and a smaller port *g* arranged to register with port *d'* when the valve is in the neutral position described above and illustrated in Fig. 19. Two small ports *h* and *i* are arranged to register interchangeably with the inlet port *c'* in either of the two power operating positions of the valve. Two other ports *j* and *k* interconnected by a cored passage in the rotor, as shown, are arranged to communicate interchangeably with the port *d'* in either of said power operating positions of the valve. Thus, in Fig. 11, which corresponds with Fig. 20, the port *h* is shown in communication with the port *c'*, and the port *k* in communication with the port *d'*. Under these conditions, the oil entering the bonnet 85 at *h* is delivered at *i* to the pipe *b* extending to the rear end of the cylinder 41 and the oil discharged from the front end of the cylinder through pipe *a* is conducted through ports *j* and *k* to the pipe *d* extending to the reservoir 69. In the other power operating position, port *i* would become the inlet to the bonnet 85 with port *h* delivering the oil through pipe *a* to the cylinder and port *k* draining the return oil from pipe *b* to port *j* and thence through pipe *d* to the reservoir 69. The neutral position is half-way between these two extremes in which the rotor in the position of Fig. 10 is superimposed on the stator of Fig. 9 isolating the inlet port *c'* and placing the port *g* in communication with the port *d'* and ports *e* and *f* in communication with ports *a'* and *b'*, respectively, to permit manual operation of the table back and forth as illustrated and described in connection with Fig. 19.

The rotor 86, during power operation of the table, is held seated under the pressure of the oil from the pump 68, as well as under the action of the spring 90, but in the event one takes hold of the table and moves it by hand faster than the power operation will move it, the oil pressure beneath the disk from the exhausting end of the cylinder 41 overcomes the opposing spring pressure and oil pressure and unseats the rotor. While the rotor is thus unseated, enough oil from the pump and from the exhausting end of the cylinder will find its way to the other end of the cylinder and any excess will find its way to the sump. Then, whenever the quick hand movement is stopped, the rotor reseats and power operation is resumed from that point on.

65 Pump 68 and reservoir 69

Referring to Figs. 12-14, the motor 70 is mounted on a housing 98 which has a hollow extension 99 reaching into the reservoir 69 bolted onto the housing 98. The pump 68, which is of the rotary sliding vane type, although any other type suitable for the purpose may be employed, this type being preferred because of its quiet operation, is driven by the motor through a coupling 100 and has an intake 101 with a restricted port 102 close enough to the bottom of the reservoir 69 to be assured of oil even though the

reservoir may be in an unusual position. The cutting down in the size of the intake port was found to eliminate noise otherwise experienced when the intake was left unrestricted. The passage 103 is the outlet or discharge passage leading from the pump to the pipe *c* and it is with this passage that the pressure relief valve 83, previously mentioned, communicates, as indicated in Figs. 13 and 14. An air dome 104 is also provided communicating with the passage 103 to avoid hammering in the operation of the pump and accordingly further insure quiet operation of the mechanism. The oil returned to the reservoir 69 through pipe *d* is conducted through a cored passage 105 in the side of the housing 98 opening at 106 into the bottom of the reservoir 69. The reservoir is filled through an opening closed by the plug 107, and a level is maintained up to the opening closed by the plug 108. An air vent is provided in the top of the reservoir, as at 109. The pump, as stated above, is always operated in one direction, the reversal of movement of the table being obtained by shifting the valve 67 controlling the delivery of oil from the pump 25 to the working cylinder.

Switches 73 and 74

The switch 73 is in the form of a plate 110 mounted on the housing 58 of the table guide switch 32 but insulated therefrom, as indicated at 111. Two spring pressed terminals 112 and 113 are slidably mounted on the plate 110 for engagement by the arms 53c and 54c, respectively, to ground the conductor 79 which extends from the plate 110 of the switch 73 to the terminal 114 of the switch 74, a suitable clip being provided on the end of the spring of the terminal 112, as indicated in Figs. 16 and 17. Obviously, since the arms 53c—54c are grounded on the frame, the contact of either of these arms with one of the terminals 112—113 completes the circuit to ground for the conductor 79. The fact that the terminals 112—113 are spring pressed, as shown, insures maintaining a good electrical connection so long as either seat is in its forward position, and, of course, as was previously stated, where the seat is locked in its forward position so that there is no danger of the motor circuit being interrupted accidentally.

The switch 74 is shown in Fig. 18. Two pivoted contact arms 115 and 116 are spring pressed toward engagement with the opposite sides of the terminal 114. The conductor 80, previously mentioned, is connected to the terminal 80' in circuit with the arm 116, and the conductor 82 is connected to the terminal 82' in circuit with the arm 115. The arm 75 is pivoted at 117 within the casing 118, which encloses the structure just described, and this arm extends through a slot in the case and has abutments 119 and 120 on opposite sides of the projecting end at the proper elevation for engagement by the strikers 76 and 77, respectively. In that way, the arm 116 breaks contact with the terminal 114 when the striker 77 encounters the abutment 120 at the end of the forward movement of the table, and the arm 115 breaks contact with the terminal 114 when the striker 76 engages the abutment 119 at the end of the return movement of the table.

Table bumpers and locking means

Referring to Figs. 3a, 3b, and 4, it will be seen that there are rubber bumpers 121 and 122 on the shuttle 31 and crosshead 40, respectively, to cushion the impact at the limits of forward and re-

turn movement of the table. At the limit of forward movement, the bumper 121 engages the transverse frame member 123 at the front end of the guide 36. At the end of the return movement, the bumper 122 strikes an adjustable stop 124 provided on the rear support 43 of the cylinder 41. The strikers 76 and 77 are so adjusted as to properly time the engagement of the bumpers at 123 and 124 so that they will be compressed only to a slight degree and there will not be any perceptible sound or shock attendant upon the stopping of the table. The compression of the bumper 122 at 124 is of advantage in minimizing likelihood of any rattling of the table when the hearse is in motion.

Referring to Figs. 3a and 15, the table is further dovetailed and held against vibration at the front end by the entry of a dovetail projection 125 on the housing 58 in between a pair of spring pressed plungers 126 provided in a housing 127 mounted on the bottom of the table 27 at the front end thereof. The dovetail 125 enters between the plungers 126 as the guide member 29 leaves the groove 33 of the table guide switch 32 at the end of the return movement of the table and the plungers are forced apart, as clearly appears in Fig. 15, so that the spring pressure is active to prevent rattling of the table when the hearse is in motion. So long as the dovetail 125 is between the plungers 126, it is obvious that there can be no sidewise movement of the front end of the table, which would otherwise be permitted when the guide members 29 and 30 reach the limit positions shown in Figs. 3a and 3b. The shuttle 31, of course, prevents any sidewise movement of the rear end of the table in the limit position, so that the table is firmly anchored during the time the hearse is apt to be in motion. It was previously explained how the head of the guide member 29 fits under the rim of the switch 32 to hold the table down in full engagement with the various casters 37, whereby to further anchor the same and eliminate rattling.

It is believed the foregoing description conveys a good understanding of my invention. The appended claims have been drawn with a view to covering all legitimate modifications and adaptations.

I claim:

1. In a hearse of the side delivery type, the combination of a casket table movable relative to a support, guide means on said support cooperating with the table for guiding the table for forward and lateral movement thereof from a longitudinal retracted position toward and out of the side of the hearse, interfitting piston and cylinder elements disposed substantially parallel to the longitudinal axis of the casket table support, one of said elements being fixed relative to said support and the other of said elements being movable with respect thereto, said movable element being pivotally connected to the table to communicate longitudinal movement thereto and permit simultaneous lateral movement, and means for supplying working fluid under pressure to either end of the cylinder whereby to move the table in either direction.

2. In a hearse of the side delivery type, guide means having a longitudinal guide portion extending lengthwise of the hearse, and a laterally extending guide portion, a casket table having guide members one of which is movable in the longitudinal guide portion and another in the lateral guide portion to guide the table

for compound movement from a retracted position forwardly and laterally to extend out of the side of the hearse, an elongated cylinder disposed parallel to the longitudinal guide portion, a piston fitting in the cylinder, said cylinder being fixed and the piston being movable and having a rod extending from one end of the cylinder, the piston rod being pivotally connected to said table by the guide member operable in the longitudinal guide portion, and means for supplying working fluid under pressure to either end of the cylinder whereby to move the table in either direction.

3. In a hearse of the side delivery type, a guide means having a guide portion extending lengthwise of the hearse and another laterally extending guide portion, a casket table supported in said hearse and guided by said guide portions, and a fluid operated piston and cylinder mechanism for communicating movement to said table disposed substantially parallel with the first mentioned guide portion and pivotally connected to said table whereby to permit lateral movement of the table relative thereto.

25 4. In a hearse of the side delivery type, a guide means having a guide portion extending lengthwise of the hearse and other guide portions extending laterally from opposite sides of the first guide portion, a casket table supported in said hearse and guided by said guide portions, and a fluid operated piston and cylinder mechanism for communicating movement to said table disposed substantially vertically aligned and parallel with the first mentioned guide portion and pivotally connected to said table whereby to permit lateral movement of the table relative thereto.

5. In a hearse of the side delivery type, guide means having a guide portion extending lengthwise of the hearse and another laterally extending guide portion, a casket table supported in said hearse and guided by said guide portions, a working cylinder extending substantially parallel with the first mentioned guide portion, a piston fitting therein and having a rod extending from the front end of said cylinder, a cross-head on the front end of said rod, a second rod extending from the crosshead rearwardly along the cylinder, a second crosshead slidable lengthwise of the cylinder and connected to the rear end of said second rod and pivotally connected to said table to communicate movement thereto, and means for supplying working fluid selectively to either end of said cylinder to accordingly move the table in either direction.

6. A structure as set forth in claim 5 wherein the second rod is tubular, the structure including a guide rod supported in parallelism with said cylinder and fitting in the tubular second rod to guide the same.

7. In a hearse, a casket table supported in said hearse for compound movement back or forth and laterally, relatively movable piston and cylinder elements for communicating movement to the table, a manually operable switch member for controlling the direction of lateral movement of the table relative to the hearse, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, a motor for driving said

pump, switch means controlling the operation of the motor arranged to be closed automatically in the operation of the valve, and other switch means for control of the motor arranged to be closed automatically in the operation of the aforesaid switch member.

8. A structure as set forth in claim 7 wherein said valve is so constructed and so connected with said cylinder whereby it is arranged to be moved to a third position in which it allows free escape of fluid from either end of the cylinder and permits manual movement of the table in either direction independently of said motor and pump, said valve being further so constructed having a spring-seated valve member to allow normally a relatively restricted flow of fluid for power operation of the table while the valve member is seated, but a relatively unrestricted flow of fluid during manual operation of the table while the valve member is held unseated under fluid pressure.

9. A structure as set forth in claim 7 including other switch means operable automatically when the table reaches either of its limit positions to cause stopping of the motor.

10. In a hearse of the side delivery type, guide means having a guide portion extending lengthwise of the hearse and other guide portions extending laterally from opposite sides of the first guide portion, a casket table supported in said hearse and arranged to be guided by the first guide portion conjointly with either one of the other guide portions, a switch member movable to guide the table into one or the other of the latter guide portions, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, a motor for driving said pump, one switch means for controlling the operation of the motor arranged to be closed automatically in the operation of the valve, and an interdependent switch means for further controlling the operation of said motor arranged to be closed automatically in the movement of the aforesaid switch member.

11. A structure as set forth in claim 10 wherein said valve is so constructed and so connected with said cylinder whereby it is arranged to be moved to a third position in which it allows free escape of fluid from either end of the cylinder and permits manual movement of the table in either direction independently of said motor and pump, said valve being further so constructed having a spring-seated valve member to allow normally a relatively restricted flow of fluid for power operation of the table while the valve member is seated, but a relatively unrestricted flow of fluid during manual operation of the table while the valve member is held unseated under fluid pressure.

12. A structure as set forth in claim 10 including third switch means operable automatically when the table reaches either of its limit positions to cause stopping of the motor.

13. In a hearse of the side delivery type, guide means having a guide portion extending lengthwise of the hearse and other guide portions extending laterally from opposite sides of the first guide portion, a casket table supported in said

- hearse and arranged to be guided by the first guide portion conjointly with either one of the other guide portions, a switch member movable to guide the table into one or the other of the latter guide portions, a pair of seats normally disposed adjacent the front end of said table, either of said seats being movable forwardly to an out-of-the-way position relative to said table, means arranged in the movement of either seat to shift 5 the switch member so as to provide for movement of the table past the moved seat, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable 10 means for shifting the valve from one position to the other, a motor for driving said pump, one switch means for controlling the operation of the motor arranged to be closed automatically in the operation of the valve, and an interdependent switch means for further controlling the operation of said motor arranged to be closed automatically in the movement of the aforesaid switch member. 15
14. A structure as set forth in claim 13 wherein said valve is so constructed and so connected with said cylinder whereby it is arranged to be moved to a third position in which it allows free escape of fluid from either end of the cylinder and permits manual movement of the table in either direction independently of said motor and pump, said valve being further so constructed having a spring-seated valve member to allow normally a relatively restricted flow of fluid for power operation of the table while the valve member is seated, but a relatively unrestricted flow of fluid during manual operation of the table while the valve member is held unseated under fluid pressure. 20
15. A structure as set forth in claim 13 including third switch means operable automatically when the table reaches either of its limit positions to cause stopping of the motor. 25
16. In a hearse, a casket table supported in said hearse for movement back and forth, relatively movable piston and cylinder elements for communicating movement to the table, a pump for pumping working fluid under pressure into said cylinder, a fluid reservoir for supplying fluid to the pump, valve means for conducting fluid from the pump selectively into either end of said cylinder while exhausting fluid from the respectively opposite end of said cylinder into said reservoir to accordingly move the table under power in either direction, a motor for driving said pump, and a pressure relief valve for by-passing oil from the pump to the reservoir in the event of excessive resistance to movement of the table. 30
17. In a hearse of the side delivery type, guide means having a guide portion extending lengthwise of the hearse, and another laterally extending guide portion, a casket table supported in said hearse and guided by said guide portions, a fluid operable piston and cylinder mechanism extending substantially parallel with the first mentioned guide portion and connected with the table to acuate the same, and an overload relief valve communicating with the cylinder and arranged to open in the event of build up in pressure beyond a predetermined point. 35
18. In a hearse of the side delivery type, guide means having a guide portion extending lengthwise of the hearse and other guide portions extending laterally from opposite sides of the first guide portion, a casket table supported in said hearse and arranged to be guided by the first guide portion conjointly with either one of the other guide portions, a switch member movable to guide the table into one or the other of the latter guide portions, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, a motor for driving said pump, and a switch means for controlling the operation of said motor arranged to be closed automatically in the movement of the aforesaid switch member. 40
19. A structure as set forth in claim 18 wherein said valve is so constructed and so connected with said cylinder whereby it is arranged to be moved to a third position in which it allows free escape of fluid from either end of the cylinder and permits manual movement of the table in either direction independently of said motor and pump, said valve being further so constructed having a spring-seated valve member to allow normally a relatively restricted flow of fluid for power operation of the table while the valve member is seated, but a relatively unrestricted flow of fluid during manual operation of the table while the valve member is held unseated under fluid pressure. 45
20. A structure as set forth in claim 18 including other switch means operable automatically when the table reaches either of its limit positions to cause stopping of the motor. 50
21. In a hearse, a casket table supported in said hearse for movement back and forth, relatively movable piston and cylinder elements for communicating movement to the table, a pump for pumping working fluid under pressure into said cylinder, a fluid reservoir for supplying fluid to the pump, a motor for operating said pump, and a manually rotatable plate type valve normally controlling communication between the pump and cylinder and between the cylinder and reservoir, whereby to conduct fluid under pressure from the pump selectively to either end of the cylinder and simultaneously conduct fluid from the respectively opposite end of the cylinder to the reservoir to cause movement of the table under power, said valve comprising a plate normally seated to control the fluid flow specified for power operation but adapted to unseat automatically under fluid pressure when said table during power operation is moved faster by hand whereby to provide open communication between the opposite ends of the cylinder and the reservoir as required for hand operation of the table, said plate being adapted to reseat when power operation is to be resumed. 55
22. In a hearse, a casket table supported in said hearse for movement back and forth, relatively movable piston and cylinder elements for communicating movement to the table, a pump for pumping working fluid under pressure into said cylinder, a fluid reservoir for supplying fluid to the pump, a motor for operating said pump, and a manually operable valve normally controlling communication between the pump and cylinder and between the cylinder and reservoir. 60

whereby to conduct fluid under pressure from the pump selectively to either end of said cylinder and simultaneously conduct fluid from the respectively opposite end of the cylinder to the reservoir to cause movement of the table under power in either direction, said valve being so constructed and so connected with the cylinder whereby it is arranged to be moved to another position establishing free communication between the opposite ends of the cylinder and the reservoir, whereby to permit movement of the table manually independently of the pump and motor in either direction.

23. In a hydraulically operated device arranged to be operated interchangeably by power or by hand, a reciprocable part, relatively movable piston and cylinder elements for communicating movement to said part under power or arranged to be moved therewith by hand, a fluid reservoir, a pump supplied with fluid therefrom, a motor for driving said pump, and a valve communicating with the reservoir and pump and connected with the cylinder arranged in either of two operative positions to conduct fluid under pressure selectively to either end of the cylinder and simultaneously exhaust fluid from the respectively opposite end of the cylinder into the reservoir to produce movement of the part under power in either direction as desired, said valve being so constructed and so connected with the cylinder whereby it is arranged in a third position to interconnect the opposite ends of the cylinder and establish communication therefor with the reservoir, whereby to permit movement of said part manually independently of the pump and motor, said valve including a spring seated valve member which normally is seated to allow a relatively restricted flow of fluid for power operation of the reciprocable part, but is arranged to be unseated by fluid pressure to allow relatively unrestricted flow of fluid for manual operation of said reciprocable part.

24. In a hearse, a guide means comprising a main guide portion extending lengthwise of the hearse, and secondary guide portions extending laterally from opposite sides of said longitudinal guide, a casket table supported in said hearse for movement relative to said guides, a rotary switch member adjacent one end of said table arranged to be turned to guide the table into one or the other laterally extending guide, said table being always engaged at its other end in the longitudinal guide and being arranged to move lengthwise into and out of engagement in said switch member, and means for locking said table at the switch end against lateral movement when withdrawn from the switch member, said means comprising an interfitting projection and receptacle arranged to be interengaged or disengaged by lengthwise movement of the table, the one interfitting part being supported on the hearse and the other being movable with the table.

25. A hearse as set forth in claim 24 wherein the table has a headed member for guiding engagement in the switch member, and wherein said switch member is formed to provide a projecting portion arranged to engage the headed member when the switch member is turned to closed position, whereby to hold the table against upward displacement while it is also held against lateral displacement.

26. In a hydraulically operated device, a reciprocable part arranged to be moved interchangeably by power or by hand, relatively movable piston and cylinder elements for communicating

movement to said part under power or arranged to be moved therewith by hand, a fluid reservoir, a pump supplied with fluid therefrom, a motor for driving said pump, and a plate type valve communicating with the reservoir and pump and connected with the cylinder, arranged in either of two operative positions to conduct fluid under pressure selectively to either end of the cylinder and simultaneously exhaust fluid from the respectively opposite end of the cylinder into the reservoir to produce movement of the part under power in either direction as desired, said valve comprising a plate normally seated to control the fluid flow specified for power operation but adapted to unseat under a predetermined excess of fluid pressure in the cylinder in front of said piston when said part during power operation is moved faster by hand, whereby to interconnect the opposite ends of the cylinder and establish communication therefor with the reservoir to permit hand operation of the part independently of the pump and motor, said plate being adapted to reseat when power operation is to be resumed.

27. In a hearse of the side delivery type, guide means, a casket table supported in said hearse and guided by said guide means, a working cylinder, a piston fitting therein and having a rod extending from one end of said cylinder, a cross-head on the outer end of said rod, a second rod extending from the crosshead toward and along the cylinder, a second crosshead slidable lengthwise of the cylinder and connected to the adjacent end of said second rod, one of said crossheads being pivotally connected to said table to communicate movement thereto, and means for supplying working fluid selectively to either end of said cylinder to accordingly move the table in either direction.

28. A structure as set forth in claim 27, where in the second rod is tubular, the structure including a guide rod supported in parallelism with said cylinder and fitting in the tubular second rod to guide the same.

29. In a hearse of the side delivery type, guide means having a guide portion extending lengthwise of the hearse and another laterally extending guide portion, a casket table supported in said hearse and arranged to be guided by the first guide portion conjointly with the other guide portion, a switch member movable to guide the table into the latter guide portion, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, a motor for driving said pump, one switch means for controlling the operation of the motor arranged to be closed automatically in the operation of the valve, and an inter-dependent switch means for further controlling the operation of said motor arranged to be closed automatically in the movement of the aforesaid switch member.

30. In a hearse of the side delivery type, guide means having a guide portion extending lengthwise of the hearse and another laterally extending guide portion, a casket table supported in said hearse and arranged to be guided by the first guide portion conjointly with the other guide portion, a switch member movable to guide the

- table into the latter guide portion, a seat normally disposed adjacent the front end of said table movable forwardly to an out-of-the-way position relative to said table, means arranged in the movement of said seat to shift the switch member so as to provide for movement of the table past the seat, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, a motor for driving said pump, one switch means for controlling the operation of the motor arranged to be closed automatically in the operation of the valve, and an interdependent switch means for further controlling the operation of said motor arranged to be closed automatically in the movement of the aforesaid switch member.
31. In a hearse of the side delivery type, guide means having a guide portion extending lengthwise of the hearse and another laterally extending guide portion, a casket table supported in said hearse and arranged to be guided by the first guide portion conjointly with the other guide portion, a switch member movable to guide the table into the latter guide portion, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, a motor for driving said pump, and a switch means for controlling the operation of said motor arranged to be closed automatically in the movement of the aforesaid switch member.
32. In a hearse, a guide means comprising a main guide portion extending lengthwise of the hearse, and a secondary guide portion extending laterally from said longitudinal guide, a casket table supported in said hearse for movement relative to said guides, a rotary switch member adjacent one end of said table arranged to be turned to guide the table into the laterally extending guide, said table being always engaged at its other end in the longitudinal guide and being arranged to move lengthwise into and out of engagement in said switch member, and means for locking said table at the switch end against lateral movement when withdrawn from the switch member, said means comprising an interfitting projection and receptacle arranged to be interengaged or disengaged by lengthwise movement of the table, the one interfitting part being supported on the hearse and the other being movable with the table.
33. A hearse as set forth in claim 32, wherein the table has a headed member for guiding engagement in the switch member, and wherein said switch member is formed to provide a projecting portion arranged to engage the headed member when the switch member is turned to closed position, whereby to hold the table against upward displacement while it is also held against lateral displacement.
34. In a hearse, a casket table supported in said hearse for movement back and forth, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as desired, manually operable means for shifting the valve from one position to the other, and power means for operating said pump, said valve having a spring-seated valve member which is normally seated to allow a relatively restricted flow of fluid for power operation of the table, but is arranged to be unseated under fluid pressure in the event of faster movement of the table manually, whereby to allow relatively unrestricted flow of fluid required in the manual operation of the table.
35. In a hearse of the side delivery type, guide means having a longitudinal guide portion extending lengthwise of the hearse, and a laterally extending guide portion, a casket table having guide members one of which is movable in the longitudinal guide portion and another in the lateral guide portion to guide the table for compound movement from a retracted position forwardly and laterally to extend out of the side of the hearse, an elongated cylinder extending in the same general direction as one of said guide portions, a piston fitting in the cylinder, said cylinder being fixed and the piston being movable and having a rod extending from one end of the cylinder, the piston rod being operatively connected to said table by the guide member operable in the last-mentioned guide portion, and means for supplying working fluid under pressure to either end of the cylinder whereby to move the table in either direction.
36. In a hearse of the side delivery type, a guide means having a guide portion extending lengthwise of the hearse and another laterally extending guide portion, a casket table supported in said hearse and guided by said guide portions, and a fluid operated piston and cylinder mechanism for communicating movement to said table disposed substantially parallel with one of said guide portions and pivotally connected to said table whereby to permit lateral movement of the table relative thereto.
37. In a hearse of the side delivery type, guide means having a guide portion extending lengthwise of the hearse, and another laterally extending guide portion, a casket table supported in said hearse and guided by said guide portions, a fluid operable piston and cylinder mechanism extending substantially parallel with one of said guide portions and connected with the table to actuate the same, and an overload relief valve communicating with the cylinder and arranged to open in the event of build up in pressure beyond a predetermined point.
38. In a hearse of the side delivery type, guide means having a guide portion extending lengthwise of the hearse and another laterally extending guide portion, a casket table supported in said hearse and arranged to be guided by the first guide portion conjointly with the other guide portion, relatively movable piston and cylinder elements for communicating movement to the table, a pump for pumping working fluid under pressure into said cylinder, a valve arranged in one position to deliver fluid from the pump to one end of said cylinder and in another position to the other end of said cylinder whereby to produce table movement in either direction as de-

- sired, manually operable means for shifting the valve from one position to the other, a motor for driving said pump, and a switch means for controlling the operation of said motor.
- 5 39. A structure as set forth in claim 38, wherein said valve is so constructed and so connected with said cylinder whereby it is arranged to be moved to a third position in which it allows free escape of fluid from either end of the cylinder 10 and permits manual movement of the table in either direction independently of said motor and pump, said valve being further so constructed having a spring-seated valve member to allow normally a relatively restricted flow of fluid for 15 power operation of the table while the valve member is seated, but a relatively unrestricted flow of fluid during manual operation of the table while the valve member is held unseated under fluid pressure.
- 20 40. A structure as set forth in claim 38, including other switch means operable automatically when the table reaches either of its limit positions to cause stopping of the motor.
- 25 41. In a hydraulically operated device, an actuated member supported for movement back and forth, relatively movable piston and cylinder elements for communicating movement to the actuated member, a pump for pumping working fluid under pressure into said cylinder, a fluid reservoir 30 for supplying fluid to the pump, a motor for operating said pump, and a manually rotatable plate type valve normally controlling communication between the pump and cylinder and between the cylinder and reservoir, whereby to conduct fluid 35 under pressure from the pump selectively to either end of the cylinder and simultaneously conduct fluid from the respectively opposite end of the cylinder to the reservoir to cause movement of the table under power, said valve comprising a plate normally seated to control the fluid flow specified for power operation but adapted to unseat automatically under fluid pressure when said actuated member during power operation is moved faster by hand whereby to provide open communication between the opposite 40 ends of the cylinder and the reservoir as required for hand operation of the actuated member, said plate being adapted to reseat when power operation is to be resumed.
- 45 42. In a hydraulically operated device, a reciprocable part arranged to be moved interchangeably by power or by hand, relatively movable piston and cylinder elements for communicating movement to said part under power or arranged to be moved therewith by hand, a fluid reservoir, a pump supplied with fluid therefrom, a motor for driving said pump, a plate type valve communicating with the reservoir and pump and connected with the cylinder, arranged in either 50 of two operative positions to conduct fluid under pressure selectively to either end of the cylinder and simultaneously exhaust fluid from the respectively opposite end of the cylinder into the 55 reservoir to produce movement of the part under power in either direction as desired, said valve comprising a plate normally seated to control the fluid flow specified for power operation but adapted to unseat under a predetermined excess of fluid pressure in the cylinder in front of said piston when said part during power operation is moved faster by hand, whereby to interconnect the opposite ends of the cylinder and establish communication therefor with the reservoir to 60 permit hand operation of the part independently of the pump and motor, said plate being adapted to reseat when power operation is to be resumed, and a pressure relief valve connected between the pump and cylinder arranged to open in the event the pressure in the cylinder behind the piston exceeds a predetermined value.
- 65 43. In a hearse, a casket table supported in said hearse for movement back and forth, a fluid operated piston and cylinder mechanism operatively connected with the table to communicate movement thereto, means for supplying working fluid under pressure selectively to either end of the cylinder, whereby to move the table in either direction, and a pressure relief valve between the last-mentioned means and said cylinder arranged to open in the event resistance to the movement of the table results in excessive pressure in the cylinder.
- 70 44. In a hearse, a casket table supported in said hearse for movement back and forth, a fluid operated piston and cylinder mechanism operatively connected with the table to communicate movement thereto, means having fluid communication with the opposite ends of said cylinder whereby working fluid under pressure is supplied selectively to either end of the cylinder and fluid is drained from the opposite end whereby to move the table in either direction, and a pressure relief valve arranged to open in the event of excess pressure on the drain side of the piston, whereby to permit manual operation of the table at increased speed during power operation thereof.
- 75 45. In a hearse, a casket table supported in said hearse for movement back and forth, a fluid operated piston and cylinder mechanism operatively connected with the table to communicate movement thereto, means having fluid communication with the opposite ends of said cylinder whereby working fluid under pressure is supplied selectively to either end of the cylinder and fluid is drained from the opposite end whereby to move the table in either direction, a pressure relief valve arranged to open in the event of excess pressure on the drain side of the piston, whereby to permit manual operation of the table at increased speed during power operation thereof, and a pressure relief valve arranged to open in the event of excess pressure in the cylinder on the other side of the piston, whereby to stop the table during power operation in the event of excessive resistance to movement thereof.

EDWARD RICHTER.
